UNITED STATES PATENT OFFICE.

MICHAEL F. MCNIFF, OF CHICAGO, ILLINOIS, ASSIGNOR OF ONE-FOURTH TO JAY D. MILLER, OF CHICAGO, ILLINOIS.

LAST FOR MAKING SLIPPERS, LOW SHOES, OR OXFORDS.

Application filed March 16, 1925. Serial No. 16,055.

My invention relates to the manufacture of footwear or shoes, and more especially to lasts for making slippers, low shoes or oxfords.

5 The principal object of the invention is to produce a last, especially for low shoes or slippers, the heel and instep of which are so designed in shape and cross-section, that the shoe made thereon as a pattern or form, 10 will closely hug or grip the foot, but not under excessive pressure, so that the low shoe or slipper will not have the tendency to move downwardly or away from the foot when the wearer steps on the ball of the 15 foot during the act of walking.

A further object of the invention is to so construct the last that the slipper or low shoe patterned thereon, will hug the sides of the foot and the heel and will prevent 20 gapping or spreading and further prevents the low shoe or slipper from becoming unsightly at the sides and heel, and will conform to the heel of the wearer and prevent the low shoe or slipper from moving up and 25 down and cause it to remain confined at the heel, thus also preventing the usual rubbing and wearing of the hose and the forming of a blister at the heel.

Other and further objects of the invention 30 will be apparent from the drawings as the description proceeds.

In the drawings:

Figure 1 is a side elevation of a last constructed or patterned in accordance with the 35 invention, and

Figures 2 and 3 are cross-sections taken on the line 2—2 and 3—3 of Figure 1.

Referring to the drawings in detail, in 40 which like reference characters designate corresponding parts throughout the several views, the last body is designated generally at 4 and may be produced of wood or other suitable material in any preferred or known manner. The novelty of the invention consists among other features, in a novel formation of heel, and in making the last so that the shoe made or formed over said last will conform to the natural outlines of a foot when placed on the foot or in other words, 45 while the shoe is being worn. The toe portion 5 of the said last is curved up at the ball and arch but rounded in cross-section as indicated at 6 with a flat or level portion 7 at the base or bottom of the heel, also 50 rounded in cross section.

The instep, instead of being substantially straight, is curved upwardly on a convex arc as indicated at 8, projecting at 9 above and merging into and with the top edge 10 which curves downwardly and extends back 60 substantially straight to the back of the heel portion.

The particular part of the improvement relates to the heel portion, in conjunction with the cross-section of the last as will also 65 fully appear. The edge 10 projects rearwardly and the contour or outline of the heel of the last is formed by two oppositely curved meeting arcs 11 and 12 forming a reverse curvature or compound curve. The 70 upper curve or arc 11 is concave and merges into and with the convex lower part at the point where the bony part of the heel of the foot begins. By this means, the heel of the foot is confined in the heel portion 75 of the shoe between a point about centrally of the concaved arc 11 and the bottom of the heel of the shoe at a point about at the back or beginning of the arch or in front of the bottom of the heel proper. In other 80 words, a tightening or confining effect is exerted in a downward and forward direction on a diagonal line substantially as indicated by the dotted arrow line "X" as seen in Figure 1 of the drawings when the shoe 85 is spread or filled out by the pressure of the foot in the low shoe or slipper. This action retains the shoe snugly fitted and in proper position on the foot without depending upon the tightening of the fastening or lacing 90 which is solely relied upon in the low shoes or slippers as heretofore constructed in order to retain the shoe in proper position, but without success. Thus, with this new 95 construction, it is unnecessary to lace the shoe tight and this relieves the instep and ankle of the foot of pressure and enables complete freedom of motion as well as comfort to the wearer, especially in the act of 100 walking.

Figure 2 shows the cross-section of the last on the line 2—2 of Figure 1, and it will be observed that the same is tapered toward the top 10 and concaved on opposite sides as at 13 with the upper portions parallel to each other and normal or perpendicular to the top face or edge 10. In other words, the last and low shoe or slipper made therefrom is made narrower than usual in order to combine with the heel formation to pro- 110

duce the new and desirable fit heretofore described.

Figure 3 shows the cross-section of the last on the line 3—3 of Figure 1, from which it will be observed that the sides 14 are slightly concaved and slope or slant outwardly from the rounding top, that is, diverge downwardly and converge upwardly. Thus, it will be seen, that the last is generally of tapered or triangular cross-section and with the special and novel heel curvature as described, a low shoe or slipper produced thereon, will contract at the sides and draw in at the heel to tighten on the foot, with the advantages previously referred to in detail. This prevents the low shoe or slipper from gapping open at the sides and spreading at the heel, and instead of leaving the top of the heel loose, it will closely hug or grip the foot so that the low shoe or slipper will not have the tendency to move downwardly or away from the foot when the wearer steps on the ball of the foot during the act of walking.

23. While I have described my invention in detail, I am aware that many changes may be made and numerous details of construction varied throughout a wide range without departing from the principles of this invention, and I therefore, do not purpose limiting the patent granted thereon otherwise than as necessitated by the prior art.

I claim as my invention:—

1. A last having the contour of the heel formed by two oppositely curved merging arcs, the lower arc being convex and the upper arc being concave, whereby a shoe made

from the last will be contracted and tightened immediately above the bony part of the heel and tension exerted downwardly 40 toward the arch.

2. A last for low shoes or slippers having its heel cut on a reverse curve, with the lower portion rounded and the upper portion concaved to the top and curving rearwardly at the top, said last being of upwardly tapered cross-section. 45

3. A last for low shoes or slippers having its heel cut on a reverse curve, with the lower portion rounded and the upper portion concaved to the top and curving rearwardly at the top, said last being of upwardly tapered cross-section, and narrower 50 than the ordinary width.

4. A last wherein the configuration of the heel is formed by two oppositely curved merging arcs, the lower arc being convex and the upper arc being concave, said last having oppositely sloping sides at the instep and a rounded bottom and concaved sides 60 at the sides of the heel narrowed toward the top. 55

5. A last wherein the configuration of the heel is formed by two oppositely curved merging arcs, the lower arc being convex 65 and the upper arc being concaved, said last having oppositely sloping flat sides at the instep and the opposite sides of the lower portion of the heel convex and of the upper portion concaved and approaching the top 70 substantially parallel to each other and normal to the top.

In testimony whereof I affix my signature.
MICHAEL F. McNIFF.
